UNITED STATES PATENT OFFICE

93,329

DESIGN FOR A SHELF BACK LAVATORY

Raymond E. Crane, Kittanning, Pa.

Application April 21, 1933, Serial No. 47,859

Term of patent 14 years

To all whom it may concern:

Be it known that I, RAYMOND E. CRANE, a citizen of the United States, residing at Kittanning, in the county of Armstrong and State of Pennsylvania, have invented a new, original, and ornamental Design for a Shelf Back Lavatory, of which the following is a specification, reference being had to the accompanying drawing, forming a part thereof.

Figure 1 is a perspective view of the article, and Figs. 2 and 3 are plan and front elevational views respectively.

I claim:

The ornamental design for a shelf back lavatory, as shown.

RAYMOND E. CRANE.
